TOY PARACHUTE

Oliver S. Annable, Brooklyn, N. Y., assignor to
Joseph R. Bergey, New York, N. Y.

Application January 23, 1947, Serial No. 723,714

4 Claims. (Cl. 46—86)

1

This invention relates to parachutes and provides novel forms of parachutes and a method of making them. The invention has particular application to toy parachutes, but also to the making of inexpensive parachutes for various other purposes, for example the support of signals, flares and targets.

The invention provides a parachute construction which is extremely simple and very inexpensive to produce. Contrary to the conventional practice of attaching separate shroud lines to a parachute canopy, I propose to make both the canopy as well as all the shrouds from a single piece or blank of foldable material. Such material may be paper, or fabric such as silk or rayon, or any other suitable synthetic or plastic material which is strong and light enough and adapts itself to folding into a small space.

The various objects, features and advantages of this invention will appear more fully from the detailed description which follows accompanied by drawings showing for the purpose of illustration preferred embodiments of the invention. The invention also consists in certain new and original features of construction as well as combination of steps hereinafter set forth and claimed.

Although the characteristic features and steps of the invention which are believed to be novel will be particularly pointed out in the claims appended hereto, the invention itself, its objects and advantages, and the manner in which it may be carried out may be better understood by referring to the following description taken in connection with the accompanying drawings forming a part of it in which:

Figure 1 is a plan view of a square blank from which a substantially square parachute with four shroud lines may be formed;

Figure 2 is a modified form of blank for a substantially square parachute having four shroud lines, pairs of which are connected;

Figure 3 is a blank for a substantially triangular parachute;

Figure 4 is a blank for a substantially circular parachute;

Figure 5 is a perspective view of an opened parachute formed from the blank shown in Figure 1;

Figure 6 is a perspective view of an opened parachute formed from the blank shown in Figure 2;

Figure 7 is a perspective view of an opened parachute formed from the blank shown in Figure 4; and

Figure 8 shows a blank in which shroud lines

2

are formed by convolute cuts resulting in particularly long shroud lines.

In the following description and in the claims various details will be identified by specific names for convenience. The names, however, are intended to be as generic in their application as the art will permit.

Like reference characters refer to like parts in the several figures of the drawings.

10 In the drawings accompanying, and forming part of, this specification a certain specific disclosure of the invention is made for the purpose of explanation of broader aspects of the invention, but it is understood that the details may be modified in various respects without departure from the principles of the invention and that the invention may be applied to other structures than the ones shown.

15 The blank A in Figure 1 may be cut from paper or fabric or any other material light and strong enough and adapted to be folded into a small space, rice paper, silk and rayon being particularly suited as materials for the blank. The blank is substantially rectangular in outline thus permitting blanks to be cut in multiple from sheets or rolls of material without waste. The blank A is cut along cut lines 11, 12, 13 and 14 extending substantially parallel to, but spaced from, the outer edges 15, 16, 17 and 18 of the blank.

20 These cuts form strips 19, 20, 21 and 22 of the material which constitute shroud lines or shroud portions and are connected to the central portion 23 of the blank, forming the canopy of the parachute, along uncut portions 24, 25, 26 and 27. The cut lines 11, 12, 13 and 14 terminate for this reason at some distance from one another leaving the portions 24, 25, 26 and 27 uncut, wide enough, considering the tear strength of the material of the blank, to prevent tearing of the uncut portions when the parachute is in use.

25 The ends 28, 29, 30 and 31 of the strips, remote from the respective uncut portions, are adapted to be connected together in any suitable manner, for example by a suitable clip or clasp of sheet metal of the type generally used for connecting sheets of paper together, assuming the parachute is intended to be used as a toy.

30 The blank B shown in Figure 2 is likewise rectangular in outline. It is bordered by outer edges 32, 33, 34 and 35. Two internal cut lines 36 and 37 separate two shroud line forming strips 38 and 39 from the remainder 40 of the blank, the remainder forming the canopy. Each strip 38 and 39 represents two shroud lines connected at the center at 41 and 42, the ends of the shroud lines

35

being connected to the canopy 40 along uncut portions 43, 44, 45 and 46.

The centers 41 and 42 of the strips are adapted to be brought and connected together, whereby a parachute structure is formed having a substantially rectangular canopy with a shroud line extending to each of the four corners.

The blank C shown in Figure 3 is substantially triangular in outline and likewise lends itself to the cutting from large sheets or rolls of material without waste. Three cut lines 47, 48 and 49 define shroud lines 50, 51 and 52 connected to the central portion 53 of the blank along uncut portions 54, 55 and 56.

The blank D of Figure 4 is substantially circular in outline and comprises shroud portions 57, 58 and 59 separated by substantially circular cut lines 60, 61 and 62 from the central portion 63 of the blank. The cut lines terminate at some distance from one another leaving portions 64, 65 and 66 uncut, and extend substantially radially at 67, 68 and 69 to form the bottom ends of the shrouds. While three shroud lines are provided for the illustrated circular blank, it is apparent that four or more may be employed.

The ends of the shroud portions or strips may be connected in any suitable manner such as gluing, stapling, stitching or clamping.

Figure 5 shows the blank of Figure 1 with the ends of the shrouds 19, 20, 21 and 22 connected by a sheet metal clip 70 in the form of a parachutist.

Figure 6 shows a parachute made from the blank B of Figure 2 in opened condition. The center portions 41 and 42 of the shrouds 38 and 39 are brought together and clamped by a paper clip 71 which also forms the ballast of the parachute.

Figure 7 shows a parachute assembled from the blank D of Figure 4. The shrouds 57, 58 and 59 are connected to the canopy 63 along uncut portions 64, 65 and 66, the latter portion being not visible in Figure 7. The ends of the shroud are connected together by a paper clip 71. The paper clip 71 is of well-known construction and consists of a strip of sheet metal bent into the shape of a U, one leg of the U having a prong struck out therefrom, the other leg having a hole therein adapted to be engaged by a prong.

The method of making parachutes from a single blank of foldable material results in utmost simplicity of construction and a considerable saving in cost both as regards material and labor. The three or four shroud lines of the illustrated embodiments are very easy to connect by a simple quick operation, and the conventional operations of securing separate shrouds to predetermined points or portions of the canopy are eliminated.

The blanks may be cut on automatic cutting machines of the general type in common use in the paperbox industry, whereby great accuracy and a particularly low production cost is obtained.

The invention lends itself admirably to the production of toy parachutes and parachutes for advertising purposes where low cost is of importance. Such parachutes may be launched in any convenient conventional manner, for example by inserting them folded into a hollow blow tube and ejecting them therefrom by blowing into the end of the tube. The folded parachutes are then ejected from the tube to a substantial height where they open and float to the ground.

It is quite apparent that the invention may be applied with advantage to the making of para-

chutes for various other purposes, for example for carrying flares, signal lights or other relatively small objects.

For some purposes, it may be desired to have a parachute whose shroud lines are relatively long. Long shroud lines may be formed by employing convolute cuts as shown in Figure 8. The blank E in Figure 8 is substantially circular in outline and comprises three shroud lines 72, 73 and 74 separated from one another and from the central canopy portion 78 of the blank by substantially spirally extending cut lines 75, 76 and 77. The shroud lines are connected to the canopy 78 along uncut portions 79, 80 and 81. In the illustrated embodiment, each shroud line extends through approximately 240 degrees with respect to the center of the canopy, but may manifestly be made longer or shorter by extending or shortening the cut lines.

The invention thus provides a novel manner and method of making parachutes for a wide variety of uses. Evidently the invention is not limited to the particular embodiments herein shown and described but may be applied with equal benefit to many other forms of blanks. For example, hexagonal blanks may be employed which, similarly to square and triangular blanks, have the advantage of being formable from large sheets without waste. Hexagonal blanks may be formed to provide shroud lines of any desired length by employing convolute cut lines as shown in principle in Figure 8. Convolute cut lines not only result in the formation of particularly long shroud lines, but also form spirally extending shrouds which, during the descent of the parachute, impart a rotating motion to it which is very desirable for many purposes.

It is therefore apparent that various changes, additions, omissions, substitutions and other modifications may be made without departing from the spirit and the teachings of this invention.

What is claimed is:

1. A parachute made from a single blank of foldable material, the blank having strip portions cut therefrom by cuts extending substantially parallel to the edges of the blank, said strip portions forming shrouds for the remainder of the blank, the remainder forming a canopy, at least one end of each cut terminating at a distance from the edge of the blank leaving the respective strip connected to the canopy along an uncut portion of the blank; and a metal clip securing together the strip portions and providing centered ballast for said parachute, said metal clip comprising a piece of metal bent-back upon itself and gripping the strip portions between the bent-back portions of the clip, said clip being free from engagement with the canopy.

2. A parachute comprising a canopy and shroud lines, both canopy and shroud lines being formed from a single sheet of foldable material by cuts extending along, but spaced from, the outer edge of the blank, said cuts separating shroud line-forming strips from the remainder of the blank, the strips being connected to the remainder of the blank along uncut portions; and a metal clip securing together said strips at portions remote from said canopy and providing centered ballast for said parachute, said metal clip comprising a piece of metal bent-back upon itself and gripping the strip portions between the bent-back portions of the clip, said clip being free from engagement with the canopy.

3. A parachute made from a single blank of foldable material, the blank being divided by in-

ternal cuts extending along, but spaced from the outer edge of the blank, into shroud-forming strip portions and a main portion forming a canopy, the strip portions being connected to the canopy at both ends along uncut portions, the intermediate portions of the strips being adapted to be connected together for support of parachute ballast; and a metal clip connecting together said strips at said intermediate portions and providing centered ballast for said parachute.

4. A parachute comprising a canopy and shroud lines, both canopy and shroud lines being formed from a single sheet of foldable material by convolute cuts extending along, but spaced from, the outer edge of the blank and spaced from one another, said cuts separating shroud line-forming strips from the remainder of the blank, the strips being connected to the remainder of the blank along uncut portions; and a metal clip connecting together the ends 20

of said strips and providing centered ballast for said parachute, said metal clip comprising a piece of metal bent-back upon itself and gripping the ends of the strips between the bent-back portions 5 of the clip, said clip being free from engagement with the canopy.
